AIR POWERED SAW OR THE LIKE

Neville H. Romain, John C. Skeehan, and Elmer A. Olson,
all of 3112 Montrose Ave., La Crescenta, Calif.

Filed Apr. 13, 1964, Ser. No. 79,474

Term of patent 14 years

(Cl. D93—3)

FIG. 1 is a top plan view of an air powered saw or the like embodying our new design;

FIG. 2 is a side elevational view of the same;

FIG. 3 is a front end view of the same;

FIG. 4 is a rear end view of the same.

The side opposite that shown in FIG. 2 is substantially a mirror image thereof.

The dominant features of my design reside in the portions shown in full lines. The broken line showing of an air hose in FIGS. 2 and 4 is fragmentarily shown for convenience of illustration.

We claim:

The ornamental design for an air powered saw or the like, substantially as shown and described.
